UNITED STATES PATENT OFFICE.

CARL R. WAGNER AND CLYDE E. RUBOTTOM, OF PEORIA, ILLINOIS.

ARCTIC APPLIER AND REMOVER.

Application filed September 29, 1927. Serial No. 222,718.

Our invention relates more particularly to devices for use in connection with arctics, overshoes, and the like which are worn by persons who wear shoes which are provided with rubber heels.

It is well known that rubber, and rubber compounds offer an extremely high frictional resistance to movement against a surface such as that presented by the inside 10 of an arctic or overshoe, and that it is very difficult to insert the shoe which is equipped with rubber heels into an overshoe and in order to facilitate the insertion and removal of the shoe from the overshoe we provide a 15 member which at least partly encloses that part of a rubber heel which comes in contact with the overshoe, and moves with the heel during the insertion or removal of the shoe, and so our invention is directed in part 20 to a friction reducing member such as above indicated.

Our invention is also directed to means for preventing the loss or misplacing of the friction reducing member, these means consisting of a flexible member which is attached to the overshoe and to which the friction reducing member is attached, the flexible member also serving as a means to assist in the removal of the shoe from the 30 overshoe.

The novelty of our invention will be hereinafter more fully set forth and specifically pointed out in the claims.

In the accompanying drawing, Fig. 1 is a 35 perspective view of a device embodying our invention.

Fig. 2 is a broken sectional view of a shoe and an overshoe showing the use of our device in connection therewith.

The same numerals of reference are used to indicate identical parts in both figures.

As illustrating one form of device embodying our invention though without limiting ourselves to the present details of construction or arrangement of parts shown or described, but availing ourselves of all changes and modifications which may be made and which fall within the scope of the appended claims, we have shown a device 50 comprising essentially two members, the

lower being a sheet metal guard 3, and the upper being a flexible member or tape 4 of sufficient length to reach from the guard 3 to the top of the back of the overshoe for attachment thereto as at 5 in Fig. 2 in which figure the overshoe is represented in section as at 6, a part of the shoe being represented at 7, the latter being provided with a heel 8 which in turn carries a rubber heel or riser 9.

The operation of the device is as follows. 60 When it is desired to insert the shoe into the overshoe or arctic, the tape or flexible member 4 is used to raise the guard 3 out of the overshoe, after which the guard is placed in contact with the rear lower edge of the 65 rubber heel, the flexible member or tape 4 acting as a means to hold the guard in place while the shoe is being inserted in the overshoe. The guard is made of a material such as pressed metal or any other suitable 70 material which will offer a comparatively slight resistance to its movement against the rear portion of the overshoe while the heel is traveling downward into position. The guard remains between the heel of the shoe 75 and the lower inside portion of the overshoe as shown in Fig. 2, and when it is desired to remove the shoe from the overshoe, the flexible member is employed to hold the guard against the heel during the removing operation and assist in raising the shoe while the overshoe is being removed.

By attaching the guard to the tape, and by attaching the tape to the overshoe, there is no danger of losing the guards when the 85 overshoe is not in service.

The guards should be made with rounded edges so as not to injure the heel or any other portion of the shoe or the overshoe.

Having thus fully described our invention, 90 we claim:

1. In an arctic applier and remover the combination of a heel guard adapted to be placed on the heel of a shoe, and a flexible member attached to the guard and passing 95 to the upper portion of an arctic.

2. In an arctic applier and remover the combination of an arctic, a flexible member attached to the upper rear portion of the arctic, and a guard attached to the flexible 100

member and adapted to be placed over the heel of a shoe.

3. In an arctic applier and remover the combination of an arctic, a guard to be placed over the heel of a shoe and to be located in the heel portion of an arctic, and a flexible member connected to the guard and to the

upper rear portion of the arctic and being of sufficient length to extend from the guard to the upper rear portion of the arctic when the ¹⁰ guard is in the heel portion of the arctic.

CARL R. WAGNER.
